FUEL INJECTING DEVICE FOR INTERNAL
COMBUSTION ENGINESRené Jacques Henri Planiol, Paris, France, as-
signor of one-half to Joseph Schidlovsky,
Courbevoie, FranceApplication May 19, 1932, Serial No. 612,352
In France May 22, 1931

2 Claims. (Cl. 123—90)

This invention relates to the injection of fuel in internal combustion engines. It particularly concerns the means which, interposed between the source of fuel under pressure and the injectors, allow to determine the point of injection and the quantity of fuel injected.

In multi-cylinder engines, it has been proposed to feed all the injectors from one and the same source of fuel under pressure and to interpose a distributor between this source and each injector. The function of this distributor is to determine the moments at which the communication between the source of fuel and the injector is, either established, or interrupted. These distributors are kinematically connected to a movable member, usually the driving shaft, so that it is possible to vary these moments at will. The mechanical means used heretofore for that purpose cannot easily be accurately adjusted, particularly in high speed multi-cylinder engines used on airplanes.

The present invention has for its object to simplify the control of the distributors and to allow the accurate adjustment of the latter.

For that purpose, it is mainly characterized by the fact that the means controlling the distributors are not kinematically connected with the engine and are electrically actuated from circuits closed and opened by means of contacts or contact-breakers on which acts a member the movement of which is synchronized with that of the driving shaft.

Such as defined in its principle, the invention can be carried out according to various forms of construction which can differ from each other particularly by the nature of the electrically actuated control means.

The invention particularly concerns the new application of electromagnetic means to the control of the distributors.

In a form of construction which, for the moment, seems to be advantageous, the distributors are constituted by slide or rotary valves, or both sliding and rotary valves, attached to the movable armatures of electromagnets energized under the control of contact-breakers actuated by cams arranged for instance on the driving shaft.

The accompanying drawings illustrate, by way of example only, various forms of carrying the invention into practice.

Figure 1 is an axial section of a distributor provided with a sliding valve and electromagnetically controlled.

Figure 2 is a diagram of a modification of the electromagnetic control.

Figure 3 is a diagrammatic section of a needle valve controlling a delivery channel leading to the injector.

Figures 4 to 6 are electric diagrams for carrying the invention into practice.

The fuel is, in the known manner, taken from a tank and compressed in an enclosure on which are provided discharge valves calibrated for maintaining the pressure constant.

Pipes connect this tank to each of the injectors to be fed, the communication between the pipes and the injectors being controlled by a distributor.

Figure 1 shows a form of construction, according to the invention, of one of these distributors.

In a body 1, preferably arranged as near as possible to the injector 2 to be fed, is formed a bore 3 in which is fitted a cylindrical slide valve 4 restored by a spring 5. A member 6, made of magnetic metal, is provided at one end of the slide valve 4 and is arranged in the field of an electromagnet 7, constituting the movable armature of the latter. When this electromagnet is energized, the slide valve 4 is moved to the position shown in the drawings. As soon as energization ceases, the spring 5 acts for restoring the slide valve to its initial position. Both extreme positions of the slide valve can be determined by any suitable abutments.

In the body 1 are provided channels 8, 9, 10 opening in the bore 3 and communicating respectively with the injector 2, with a fuel supply pipe 11 extending from a pressure tank, and with a pipe 12 leading to the supply tank of the compressor.

Two ports 13 and 14 are provided in the slide valve and, according to the longitudinal position of the latter, cause: either conduits 8 and 10 to communicate together, the communication between conduits 10 and 12 being cut off, or conduits 10 and 12 to communicate together, the communication between conduits 10 and 11 being cut off.

During the entire energization of the electromagnet 7, the fuel is delivered through the injector 2. As soon as this energization ceases, the communication is cut off and the injection suddenly ceases, when the conduits 10 and 12 are in communication.

For preventing the combustion gases from escaping through the conduit 12, a check valve 15 can be provided on the delivery pipe leading to the injector.

The leakage of fuel, if it occurs, collects in the

grooves 16 and returns, through channels 17, to the pipe 12.

The arrangement shown in Fig. 2 can also be adopted. In this arrangement, the slide valve 4 is attached to a lever 18 pivoted at a fixed point 19 and carrying one or two magnetic bodies 8 arranged between two electromagnets 7. The energization of one of the electromagnets ensures the movement of the slide valve in one direction, 10 that of the other electromagnet restores it to its initial position.

Instead of directly controlling the admission of fuel to the injector, the slide valve can be so devised as to control, through suitably arranged 15 ports, the communication between the conduits 11 and 12 of Fig. 1 and the connecting branches 20 and 21 of a fluid-tight casing 22 partitioned by a distortable diaphragm 23 which can be replaced by a piston. The diaphragm or piston 23 carries a needle valve 24 controlling a delivery 20 channel 25 leading to the injector 26. According as the pressure predominates on one or the other of the faces of the diaphragm or piston 23, the needle valve 24 closes or uncovers the inlet of 25 the delivery channel 25. The two extreme positions of the slide valve respectively determine: the communication between the chamber 27 of the casing 22 and the pipe 11 (Fig. 1), whilst the chamber 28 of the casing communicates with the 30 pipe 12 (Fig. 1); the communication between the chamber 28 of the casing 22 and the pipe 11, whilst the chamber 27 communicates with the pipe 12.

In the first case, injection takes place; in the 35 second case, the injection is interrupted by application of the needle valve 24 on its seat.

Various means for controlling the energization 40 circuits of the electromagnets controlling the distributors are diagrammatically illustrated in Figs. 4 to 6.

In the example of Fig. 4, a cam 29 rigidly secured on a spindle kinematically connected to this shaft, acts upon a conducting or contact-breaking lever 30, the free end of which is movable between two contact pieces 31 and 32 so spaced apart that the contact-breaker cannot simultaneously come in engagement with the said contact-pieces. When the contact-breaker is in engagement with the contact piece 32, a condenser 33 is connected to a source of current 34 which charges it. When the contact-breaker is in engagement with the contact piece 31, the condenser 33 is arranged in the energization circuit of the electromagnet or electromagnets 7 controlling the distributor. Energization of the 45 electromagnet 7 ensures the beginning of the injection; the adjustment of this point is easily obtained by causing the unit 30, 31, 32, mounted on a suitable support, to rotate about the cam. 50 The duration of the injection can be adjusted by variation of the charge tension of the condenser, the duration of the energization of the electromagnet or electromagnets varying with this tension. Obviously, several condensers can be provided, one energizing the electromagnet determining the beginning of the injection, the other energizing that terminating the injection, in the case of an arrangement such as that diagrammatically illustrated for instance in Fig. 2.

Fig. 5 diagrammatically illustrates an arrangement of this kind. Two cams 35 and 37 are rigidly secured on one and the same shaft connected to the shaft of the engine and act on contact-breakers 38 and 38^a, respectively. The cams can have 75 any profile, as only the point of engagement of

the contact-breakers is important. Condensers 39 and 40 are charged by the source of current 41 and their discharge in the electromagnet 7 and electromagnet 7^a ensures the opening and closing of the slide valve such as 4 of Figs. 1 and 2. 5

Resistances 42 and 43 are connected in series with condensers 39 and 40, but they can also be connected with the electromagnets 7 and 7^a and, in particular, they can form a part of the windings of these latter, thus allowing to reduce their 10 cumbersomeness.

The resistances 42 and 43 are adapted to ensure the regulation within critical limits of operation

$$(R^2 = \frac{4L}{c})$$

(if L=mean self-induction coil of an electromagnet and R its total effective resistance) so as to use an aperiodic discharge current. Without these resistances, the slide valve 4 can be caused to move two or more times instead of only once, according to the more or less important damping action of the oscillating discharge.

The condensers are during the greater part of the time connected to the source of current 41. When it is desired to begin the injection, the cam 36 causes 38 to discharge in the electromagnet 7, this opening the slide valve 4 and leaving it open as long as the cam 37 has not caused 40 to discharge in 7^a. For terminating the injection, 40 is discharged in 7^a by the closing cam 37. The adjustment of the point of injection is obtained by adjusting both contact breakers 38 and 38^a relatively to the engine and the period of injection is adjusted by displacement of the contact breaker 38 relatively to the contact breaker 38^a.

Concerning multi-cylinder engines, as many pairs of condensers can be used as there are cylinders, but a single condenser of each type can also be employed for all the cylinders.

In this case, the arrangement is such that a condenser discharges in the electromagnet controlling a definite slide valve only during an angular interval smaller than

$$\frac{360^\circ}{n}$$

if n is the number of cylinders of the engine.

The diagrammatic view of Fig. 6 shows an arrangement for an engine having three cylinders. The three electromagnets 44, 45 and 46 which each ensures the opening of the slide valve of a definite cylinder are connected to the condenser 47 by contact pieces 48, 50 and 51 placed in the path followed by a wiper 55 which rotates together with the driving shaft. One of the poles of a source of current 48 is connected to the condenser, the other pole being connected to three contact pieces 52, 53 and 54. Every time the wiper comes in engagement with one of the contact pieces 52, 53, 54, the condenser 47 charges. The condenser discharges when it comes in engagement with one of the contact pieces 48, 50 and 51.

The same arrangement is used for controlling the three electromagnets which ensure the closing of the distributors. In this case, the wiper 55 is suitably displaced in rotation with respect to the wiper of the arrangement relative to the electromagnets which control the opening of the 70 distributors but all the other elements are the same.

What I claim as my invention and desire to secure by Letters Patent, is:—

1. In an electromagnetic device for feeding in-

jection engines with fuel, distributors controlling the injection of fuel in the combustion chambers, an electromagnet which acts upon excitation for opening the distributor, a second electromagnet which acts upon excitation for closing the distributor, a source of continuous current, two condensers arranged in shunt at the terminals of the said source of current, an exciting circuit for each electromagnet connected in series to each of the said condensers, a switch adapted to connect the exciting circuit of the first electromagnet with one of the condensers or inversely to connect the said condenser to the source of continuous current and a second switch for effecting the aforesaid operations with the second electromagnet and the other condenser and the source, a cam for actuating each of the said switches and means for rotating the said

cams in synchronism with the engine to be fed with fuel.

2. In an electromagnetic device for feeding injection engine with fuel, electromagnets, distributors controlling the injection of fuel in the combustion chambers controlled by the excitation of said electromagnets, at least one condenser in an electric circuit, a source of continuous current, at least one switch for connecting in series the said condenser alternately with the 5 windings of the electromagnets and with the source of continuous current, a resistance connected in series with the circuit of each condenser and with the winding of the electromagnet for obtaining an aperiodic discharge and means 10 for actuating the said switch in synchronism with the engine to be fed with fuel.
